UNITED STATES PATENT OFFICE.

CHARLES F. MIDDLEBROOK, OF BINGHAMTON, NEW YORK.

TELEPHONE-DIRECTORY.

1,303,100.

Specification of Letters Patent.

Patented May 6, 1919.

Application filed June 8, 1916. Serial No. 102,510.

To all whom it may concern:

Be it known that I, CHARLES F. MIDDLEBROOK, a citizen of the United States of America, and resident of Binghamton, in 5 the county of Broome, in the State of New York, have invented new and useful Improvements in Telephone-Directories, of which the following, taken in connection with the accompanying drawings, is a full, 10 clear, and exact description.

This invention relates to certain improvements in telephone directories adapted to be used more particularly on the standards of desk phones, the main object being to provide 15 a simple and comparatively inexpensive device of this character capable of being easily and quickly placed upon the standard of any desk phone for turning movement, and also of receiving a relatively large number 20 of the most frequently used names and numbers of subscribers for ready reference while awaiting response from the central office.

I am aware that many devices have been 25 proposed for this purpose, but I believe that I am the first to employ a multi-sided transparent case open at both ends and divided through one side to enable it to be easily and quickly placed upon the standard of a 30 desk phone, in combination with separate placards bearing the names and numbers of the subscribers on each of its several faces.

Other objects and uses relating to specific 35 parts of the device will be brought out in the following description.

In the drawings—

Figure 1 is a perspective view of a desk phone showing my improved directory thereon.

40 Fig. 2 is an enlarged horizontal sectional view taken on line 2—2, Fig. 1, omitting the telephone.

Fig. 3 is an enlarged vertical sectional view taken in the plane of line 3—3, Fig. 2.

45 As illustrated, this directory comprises a case —1— having a multiplicity of, in this instance three, substantially flat rectangular sides —2—, all made of a single piece of celluloid or similar comparatively inexpensive 50 transparent material folded along transverse parallel lines equally distant from each other, and the ends brought together at one corner around the standard, as —a—, of the telephone —A— and secured together by 55 any suitable fastening means, as eyelets

—3—, thus producing, in this instance, a triangular case.

This case is preferably open at both ends and made of any convenient size, preferably of just sufficient interior area to receive the standard —a— and permit the case to be turned thereon with the lower end resting upon the base, as —a'—, of the phone.

The lower edges of the several sides of the case are preferably crimped or turned 60 inwardly and upwardly to form supporting flange —4— for the lower edges of a series of, in this instance three, separate placards —5— of paper, cardboard or other suitable material of substantially the same area as 65 the corresponding sides of the case so as to lie closely adjacent to the inner faces thereof with the printed matter, indicating the subscribers' names and numbers, facing outwardly so as to be readily visible through 70 the transparent sides of the case, said flanges serving as stops to limit the downward movement of the placards.

The object in making these cards separate 75 from each other and from the case is to 80 enable any one of them to be removed and replaced from the top without disturbing the others when it is desired to revise the list of names and numbers thereon.

The triangular form of case is found to 85 be the most desirable for use with separate placards for the reason that the vertical edges of each card are held in place by the adjacent edges of the other cards and by the acute angles at the corners which form vertical guides for the cards, thereby causing 90 said cards to lie flatwise close to the flat transparent sides of the case without extra fastening means.

The flanges —4— at the bottom also serve 95 to hold the cards flatwise against the inner faces of the side of the case, and furthermore reinforce the entire case against buckling, and at the same time enable it to be turned more easily upon the base —a—.

100 The case and blank-ruled cards may be furnished to the subscriber flatwise, and afterward folded by the subscriber along prescribed lines and placed around the standard of the telephone, and then the meeting ends 105 secured together by the eyelets —3—, whereupon the desired subscribers' names and telephone numbers may be written upon the cards which may then be inserted in place 110 from the top downward within the case with

the assurance that the lower edges will rest upon the flanges — 4.

If, at any time, it is necessary to revise the list of subscribers' names and numbers 5 on any one of the cards, it may be readily withdrawn upwardly from the interior of the case and either revised or replaced by another card without removing the case from the standard.

10 What I claim is:

1. A telephone directory comprising a triangular case having transparent sides forming acute angle guides at the corners, and separate placards, one for each side, slide- 15 able vertically in said guides across the inner faces of the transparent sides.

2. A telephone directory comprising an upright triangular case having flat transparent sides and inturned flanges along the 20 lower edges thereof, and number plates

loosely inserted from the top downward across the inner faces of the transparent sides and having their upright edges engaging in the angles of the case and their lower edges resting on the underlying flanges. 25

3. A telephone directory comprising a single strip of transparent bendable material bent into triangular form and having its ends secured to each other to form an upright transparent case open from top to bottom, in combination with placards slideable vertically across the inner faces of the transparent sides and guided in the acute angles at the corners. 30

In witness whereof I have hereunto set 35 my hand this 31st day of May, 1916.

CHARLES F. MIDDLEBROOK.
